UNITED STATES PATENT OFFICE.

SHERMAN L. ROBBINS, OF CHICAGO, ILLINOIS.

ROTARY EXPLOSIVE-ENGINE.

No. 886,641.

Specification of Letters Patent.

Patented May 5, 1908.

Application filed December 22, 1904. Serial No. 237,869.

To all whom it may concern:

Be it known that I, SHERMAN L. ROBBINS, a citizen of the United States, residing at Chicago, in the county of Cook and State of Illinois, have invented a new and useful Improvement in Rotary Explosive-Engines, of which the following is a specification.

This invention relates to rotary explosive engines.

10 The object of the invention is to provide a construction of rotary engine which is simple and efficient in operation.

A further object of the invention is to provide an explosive engine of the rotary type 15 wherein the explosions are effected in rapid succession, and the effects of the rapid explosions of the charge being successively transmitted to or imposed upon the rotating part of the engine.

20 A further object of the invention is to provide an explosive engine in which efficient means are provided for maintaining the engine cool when in operation.

A further object of the invention is to provide means for efficiently exhausting the exploded gases.

25 A further object of the invention is to provide means for efficiently controlling the supply of the explosive agent employed, to the 30 explosion chambers.

Other objects of the invention will appear more fully hereinafter.

The invention consists substantially in the construction, combination, location and arrangement of parts, all as will be more fully hereinafter set forth, as shown in the accompanying drawing, and finally pointed out in the appended claims.

Referring to the accompanying drawings, 40 and to the various views and reference signs appearing thereon,—Figure 1 is a view in longitudinal section of an explosive engine embodying the principles of my invention, the plane of section being indicated by the line 1, 1, Fig. 2, looking in the direction of the arrows. Fig. 2 is a view in transverse section of the same on the line 2, 2, of Fig. 1, looking in the direction of the arrows. Fig. 3 is a view in end elevation. Fig. 4 is a broken 45 detail view in section on the line 4, 4, of Fig. 1, looking in the direction of the arrows, showing the valve port disk in transverse section and the commutator for the spark apparatus, with their conducting and insulating segments and associated brushes in elevation. Fig. 5 is a broken detail view in 50 section on the line 5, 5, of Fig. 3. Fig. 6 is a diagrammatic view of the wiring of the ignition mechanism. Fig. 7 is a broken detail view in section, of a spark plug employed 60 in connection with the ignition mechanism. The same part is designated by the same reference sign wherever it occurs throughout the several views.

In the accompanying drawing, reference 65 sign A designates the shaft to be rotated, said shaft being journaled in bearings formed centrally in a fixed cylindrical casing B. Mounted upon shaft A, and arranged centrally within the inclosing casing B, and 70 keyed to rotate with shaft A, is the rotary piston, the hub of which is indicated by reference sign C, comprising radiating arms or spokes D, each radiating spoke D being connected at its peripheral edge to the next adjacent radiating spoke lying on opposite sides thereof through a bridge E. Each connecting bridge E is formed with a short section F thereof of cylindrical contour concentric with the axis of rotation of main shaft A, 75 such cylindrical portion extending from one of the spokes with which such bridge is connected a short distance towards the direction of rotation of the piston. At its other end each bridge is provided with a wall portion 80 G, extending radially with respect to the axis of rotation of shaft A, while the intermediate connecting portion of the bridge E is somewhat tangentially inclined towards the axis of rotation of such shaft from the cylindrical 85 portion F thereof. By reason of this construction, pockets or recesses H are formed in the peripheral surface of the rotary piston, the wall G of which is radial with respect to the piston. The piston revolves within an 90 inner sleeve portion J of the fixed casing B, the inner wall of such sleeve J forming the chamber in which the rotary piston operates being provided with cylindrical portions or surfaces K concentric with the cylindrical 95 portions or portions F of the bridges E, and co-operating with such portions F of the piston to form a close fit or bearing for the rotary piston within the casing. If desired, and in order to prevent leakage of the explosive agent employed, the cylindrical portions 100 F of the piston may be provided with suitable packing, indicated at L, arranged to co-operate with the cylindrical surfaces K of the stationary casing. The casing J is provided with tangential passages, forming 105 chambers M, the pockets or recesses H of the 110

piston successively opening into communication with each passage M of the casing as the piston rotates, and each pocket or recess H being successively cut off or closed to one passage M as it opens to the next adjacent passage M in the cycle of operation of the device. Communicating with each passage M, is the delivery end of a short section of pipe N, the receiving end of such section of pipe being arranged in position, as indicated in Figs. 1 and 5, to be brought successively into register with a port opening O formed in the flange P of a cup-shaped disk R mounted upon and rotating with shaft A, and which I will hereinafter refer to as the valve port disk. Coöperating with each short section of pipe N, is a corresponding section of pipe S, having its delivery end arranged on the opposite side of the flange P of the valve port disk with reference to the coöperating end of pipe section N, and also controlled by the ports O in such flange. In other words, the flange P of valve port disk R operates between proximate ends of each pair of pipe sections N S, and the port openings O in such flange serve the purpose of opening communication between such pipe sections. At its receiving end, each of the pipe sections S communicates with an annular supply chamber A' formed in the stationary casing of the apparatus, to which the explosive agent—as gas, for instance—is delivered through a delivery pipe B' from any suitable or convenient source, the supply of such medium being controlled, when desired or required, by means of a globe or other convenient form of throttle valve C' arranged in the supply pipe B'. Through one of the side walls of the stationary casing forming the chamber in which the piston rotates, are formed a series of exhaust openings D', each delivering through a passage E' (see Fig. 1) into an annular chamber or passage F', with which communicates an exhaust pipe G'. The exhaust openings D' are so relatively arranged as that during the rotation of the piston each of the pockets or recesses H formed in the peripheral surface of such piston is brought into register with an exhaust opening or port D' immediately succeeding the explosion of the explosive medium within such pocket or recess and its associated chamber M in the stationary casing, so that immediately after such explosion the gases generated may be exhausted from both such chamber M and recess H through the exhaust port D', passage E', chamber F' and exhaust pipe G'. If desired, the exhaust pipe G' may lead to a vacuum pump, where-by the gases of the explosion may be efficiently drawn or sucked from the engine.

Any simple, suitable, or convenient apparatus may be employed for igniting the explosive charge within the chambers M and their associated and coöperating recesses H.

I have shown a simple arrangement, wherein a spark plug H' is arranged to extend into each chamber M of the casing. The wires from each spark plug lead to a pair of brushes J', suitably supported upon disk K', journaled for rocking movement upon shaft A, and to which is connected a handle L', by which such disk may be rotatively displaced. One member of each pair of brushes J' is arranged to bear upon a conducting ring M' (see Fig. 1) of a commutator, designed to be connected to any suitable source of electric current, and the other member of each pair of brushes J' is arranged to bear against a ring of commutator segments N' composed of alternating conducting and insulating segments, as clearly shown in Fig. 4, each conducting segment being suitably connected, in any simple or ordinary manner, with the other side of the source of current supply. A simple and suitable wiring arrangement for the ignition mechanism is indicated diagrammatically in Fig. 6, wherein the inner circle is connected to one side of a source of current, while the exterior circle is connected to the other side of the source of current. The inner circle represents electrically the conductor ring, M', see Fig. 1, said ring being connected electrically with the inner circle through the radial lines shown in Fig. 6.

Tracing the circuit of the spark apparatus, at the instant of a spark it will be seen that the current will flow from one side of the source of current through the spark plug H', or other form of spark producing mechanism, thence to the brush J', which is bearing upon a conductor portion of the segment ring, thence through the sleeve upon which said segment ring is carried to the conductor ring M', see Fig. 1, thence to the brush J', bearing upon the conductor ring, and thence to the return or other side of the source of current. While I have shown a particular form of spark plug and wiring connection therefor, I do not desire to be limited or restricted thereto. The commutator rings M' N' are carried upon a sleeve O' mounted upon and keyed or otherwise fixed to rotate with shaft A.

In practice, and in order to maintain the casing of the engine cool during the operation thereof, I prefer to form the same with interior passages P', with which communicates a supply pipe R', through which water or other suitable cooling medium may be supplied, and from which passages such cooling medium may be exhausted through an out-flow pipe connection S' (see Fig. 3).

If desired, and in order to compensate for the frictional wear produced by the travel of the flange of the rotary valve port disk R past and between the proximate ends of pipe sections N S, and so as to maintain efficient packing at this point to prevent leakage of the explosive agent, I may employ caps A² sleeved over the ends of pipe sections N S,

and yieldingly pressed in any convenient manner, as, for instance, by means of springs B² interposed between a stop washer C² on said pipe sections and its associated cap. These caps being yieldingly pressed against the flange of the valve port disk, not only serve the purpose of preventing leakage at this point, but also of compensating for any wear due to the friction developed through 10 the rotation of such flange.

The lever L', through which the disk K' carrying the brushes of the sparking apparatus may be rotatively displaced, is normally held in retracted position, from which position 15 said lever and disk may be rotatively displaced, when occasion therefor arises, against the action of a spring D² (see Fig. 3) tending to return or restore said lever to its initial position.

20 In practice, I prefer to employ an odd number of sets of gas supply pipe sections N S, an odd number of exhaust port openings D', an odd number of sets of brushes J', and an odd number of chambers M in the stationary casing, and preferably the number of such gas supply pipe sections, exhaust ports, brush sets and chambers, should be the same, and I employ a greater number of valve openings or ports O in the valve disk, and a correspondingly greater number of conductor segments in the commutator ring N', and a correspondingly greater number of recesses or pockets H in the piston. Thus, in the particular form shown, to which, however, my 25 invention is not to be limited or restricted, I employ five sets of gas supply pipe sections N S, five exhaust port openings D', five sets of brushes J' and five chambers M in the stationary casing, and six conducting commu- 30 tator segments, six port openings O in the flange P of valve R, and six pockets or recesses H in the piston. The object of this is that with a greater number of pockets or recesses H in the piston than chambers M in 35 the casing, the piston will always stop in such position that a casing chamber M is in communication with a piston pocket or recess H, and a valve disk port opening O will always be in position to open communication be- 40 tween the pair of gas supply pipe sections N S corresponding to the particular chamber M of the casing and pocket or recess H of the piston which are in communication with each other. Consequently, I avoid dead- 45 centers, and am enabled to start the engine into operation at any time after the supply of gas is turned on, through the control valve C', by merely producing a spark in the particular chamber M and pocket or recess H 50 which is in such relative position as to receive an explosive charge.

By providing the lever L', by which the brush support K' is rocked, the desired explosion may be effected by simply rocking 55 said lever, and when an explosion occurs the

rotative movement imparted thereby to the piston sets the piston into rotation, thereby rotating shaft A, and hence beginning the cycle of continuous operation of the apparatus, thereafter the chambers M and pockets 70 or recesses H being successively brought into communication with each other to receive a charge of the explosive agent, such explosion being effected, thereby imparting a further kick of rotative movement to the 75 piston, and when said chamber and pocket is brought into communication with an exhaust port, such pocket or recess receives its next charge of the explosive agent; and in the particular form illustrated, since there 80 are five chambers M of the casing and six pockets H of the piston, it will be seen that thirty explosions occur at each complete revolution of the piston, each explosion acting upon such piston to impart rotative 85 movement thereto. It will be observed that each pocket or recess of the rotary piston presents a radial wall G, against which the pressure developed by the explosion is exerted, and tending to kick or rotatively dis- 90 place the piston, and as the explosions occur in each pocket or recess and its associated chamber successively as such pocket or recess successively passes the chambers M, it will be observed that a rapid succession of rotative impulses are imparted to the piston, each tending to rotatively displace the same, the number of which impulses being dependent upon the number of pockets or recesses in the piston and associated chambers, sparking 95 apparatus segments, and admission or supply mechanism for the explosive agent. 100

In practice I propose to employ an explosive agent of suitable character, such as gas, and to deliver the same through the supply pipe B' to the engine under a sufficient degree of pressure to enable the same, when exploded in the explosion chambers and pockets or recesses of the piston, to impart a 105 rotative movement to the piston. 110

Of course it will be understood that at the instant an explosion occurs in any of the explosion chambers and associated pocket or recess, the flange P of the valve port disk will have moved into such position as to 115 carry the port opening therethrough, through which the supply or charge of gas has been admitted to such explosion chamber and pocket or recess, past or beyond the pipe sections N S, and consequently when the explosion occurs the pressure thereof, which works backward through chamber M and its associated pipe N, is delivered upon the flange P of disk R, and is yieldingly resisted at the point of impact upon such flange by 120 the spring support for the cap A² lying immediately below the same. 125

It is believed that the construction and operation of the engine will be readily understood from the foregoing description 130

taken in connection with the accompanying drawings, but, briefly stated, the operation is as follows: When it is desired to start the engine, the valve C' in the supply pipe B' is opened, whereupon a supply of the explosive charge is delivered into the annular chamber A', and thence through one of the set of pipe sections S N, and a valve port O in the flange P of disk R, into whichever chamber M of the casing happens to be at that moment in communication with a pocket or recess H of the piston, and by reason of the fact that there are a greater number of pockets or recesses H in the piston than there are chambers in the casing, at least one of such pockets or recesses of the piston will be in communication with a chamber, in whatever position the piston may have been previously arrested or stopped. Now, by rotatively displacing the brush supporting disk K' by manipulating lever L', a spark will occur in each of the chambers M. The spark occurring in the chambers which are cut off from gas supply is, of course, without effect, while the spark occurring in the particular chamber M which has received a charge of the explosive agent results in an explosion, thereby imparting to the piston a rotative impulse sufficient at least to carry such piston in its rotative movement into position to automatically open another of the peripheral pockets or recesses G to a chamber M, which by the same rotative movement of shaft A receives a charge of the explosive agent through a valve port O through the annular chamber A'. At the same time, the commutator is rotatively displaced a distance sufficient to complete the necessary circuit connections to effect a spark in the second chamber thus charged with the explosive agent, thereby imparting a second rotative impulse to the piston, and so on, a charge of the explosive agent being received in each pocket or recess H of the piston, and being exploded therein as it passes each of the chambers M of the casing, and being opened to exhaust prior to receiving the next charge. In this manner, explosions of high frequency are effected, each imparting or resulting in rotative impulses being delivered to the piston, and hence also to the shaft to be rotated. The power developed in the engine may be regulated in any suitable or convenient manner, as, for instance, by regulating, through the main throttle valve C', the amount of gas supplied to the engine. When the piston is once set in motion its cycles of operation become consecutive and are accomplished entirely automatically, the various explosion chambers being successively opened to a supply of the explosive agent, and then closed to the supply as well as to exhaust, the explosive agent then being exploded, and finally exhausted of the gases of the explosion, and again charged with the explosive agent. In

this manner, rotation of the piston, and the shaft upon which it is mounted, is inaugurated and maintained.

It is obvious that many variations and changes in the details of construction and arrangement would readily occur to persons skilled in the art and still fall within the spirit and scope of my invention. I do not desire, therefore, to be limited or restricted to the exact details shown and described. But

Having now set forth the object and nature of my invention, and a construction embodying the principles thereof, what I claim as new and useful and of my own invention, and desire to secure by Letters-Patent, is:

1. In a rotary explosive engine, a piston having pockets or recesses in the periphery thereof, an inclosing casing within which said piston is mounted to revolve, said casing having a plurality of chambers with which the pockets or recesses of the piston successively communicate, the number of pockets or recesses in the piston exceeding the number of chambers in the casing, a single valve for controlling the supply of an explosive agent to all of said chambers successively, means arranged in each chamber for exploding the agent with said chamber, and means for exhausting the exploded gases from such chambers.

2. In a rotary explosive engine, a piston having pockets or recesses in the periphery thereof, an inclosing casing within which said piston is mounted to revolve, said casing having a plurality of chambers with which the pockets or recesses of the piston successively communicate, a single valve for controlling the supply of an explosive agent to all of said chambers successively, means arranged in each chamber for exploding the agent within said chamber, and means for exhausting the exploded gases from such chambers.

3. In a rotary explosive engine, a piston having pockets or recesses formed in the peripheral surface thereof, a casing within which said piston is mounted to revolve, and provided with chambers in the interior annular surface thereof with which said pockets or recesses successively communicate as the piston revolves, a single valve for automatically controlling the supply of an explosive agent to all of said chambers successively, means for exploding the charge of explosive agent within said chamber, and means for opening communication between said chambers and an exhaust.

4. In a rotary explosive engine, a piston formed with radial spokes, bridges connecting said spokes, said connecting bridges being arranged tangentially to form pockets or recesses in the periphery of the piston, an inclosing casing within which said piston is mounted to rotate, and provided with chambers upon the interior annular surface there-

of with which said pockets or recesses successively communicate during the rotative movement of the piston, said chambers being spaced around the piston at equal intervals, a single valve for controlling the supply of an explosive agent to all of said chambers successively, means arranged in each chamber for exploding such agent within said chamber, and means for opening said chambers and pockets or recesses successively to exhaust.

5. In a rotary explosive engine, a piston having radial spokes, bridges connecting adjacent spokes, said bridges being arranged in tangential relation with respect to the path of rotation of the pistons to form peripheral pockets or recesses in the piston, said bridges having curved portions concentric with the axis of rotation of the piston, an inclosing 10 casing within which said piston is journaled to rotate, and provided with curved portions coöperating with the curved portions of the bridges of the piston to form a bearing therefor, said casing having chambers formed in 15 the interior annular surface thereof with which the pockets in the piston successively communicate, means common to all of said chambers for supplying an explosive agent to said chambers successively, means arranged 20 in each chamber for exploding said agent within said chambers, and means for successively opening said pockets and their communicating chambers to exhaust.

6. In a rotary explosive engine, a piston 25 having radial spokes, bridges connecting adjacent spokes and arranged in inclined or tangential relation with respect to the path of rotation of the piston, and having radially arranged portions, thereby forming peripheral pockets or recesses in the piston, a casing 30 within which said piston is journaled to rotate, and having chambers formed in the interior annular surface thereof with which said pockets or recesses successively communicate, means common to all of said chambers for supplying an explosive agent to said chambers successively, means arranged in 35 each chamber for exploding such agent within such chambers, and means for exhausting 40 the exploded gases from such chambers and pockets or recesses.

7. In a rotary explosive engine, a piston 45 having radiating spokes, bridges connecting adjacent spokes, said bridges having a portion thereof arranged in concentric relation with respect to said piston, and a portion thereof in radial relation with respect to said piston, the intermediate portions of said bridges being tangential to the path of rotation of the 50 piston, thereby forming peripheral pockets in the piston, a casing within which said piston is journaled to rotate, said casing having concentric bearing surfaces with which the concentric curved surfaces of the bridges coöperate, said casing also provided with cham-

bers in the interior annular surface thereof, the pockets or recesses of the piston being adapted to successively communicate with said chambers during the rotations of the piston, means common to all of said chambers 55 for supplying an explosive agent to said chambers successively, means for exploding the agent within such chambers and their registering pockets or recesses, and means for opening said chambers or recesses successively to exhaust.

8. In a rotary explosive engine, a piston, a shaft with which said piston is mounted to rotate, said piston having radial spokes, bridges connecting adjacent spokes, said bridges each having a radial portion at the forward spoke of the piston with reference to the direction of rotation thereof, and an intermediate portion between the spokes connected thereby, which intermediate portion is inclined outwardly from the forward to the rear spoke which it connects, thereby forming peripheral pockets in the piston, a casing within which said piston is mounted to rotate, said casing having chambers formed in 60 the interior annular surface thereof with which the peripheral pockets or recesses of said piston successively communicate, means common to all of said chambers for supplying an explosive agent to said chambers successively, means for exploding such agent within said chambers, and means for opening 65 said chambers and their communicating pockets or recesses to exhaust.

9. In a rotary explosive engine, a piston 70 having a plurality of peripheral pockets or recesses formed therein, a casing having a plurality of chambers formed in the interior annular surface thereof, said piston journaled to rotate within said casing, the number of 75 peripheral pockets or recesses in the piston being greater than the number of chambers in the casing, means common to all of said chambers for supplying an explosive agent to said chambers successively, means arranged in each chamber for exploding said agent within such chambers, and means for exhausting 80 said chambers, and the pockets or recesses in communication therewith.

10. In a rotary explosive engine, a piston 85 having a plurality of peripheral pockets or recesses, a casing within which said piston is journaled to rotate, said casing having a plurality of chambers formed in the interior annular surface thereof, the pockets or recesses 90 in the piston being brought successively into communication with said chambers, the number of pockets or recesses exceeding the number of chambers in the casing, means common to all of said chambers for successively opening said chambers to communication with a source of explosive agent only when such chambers communicate with a peripheral pocket or recess of the piston, means for exploding the agent within such chambers, 95 100

and means for opening said chambers, and their communicating pockets or recesses, to exhaust.

11. In a rotary explosive engine, a piston having pockets or recesses, a casing within which said piston is mounted to rotate, and having chambers formed in the interior annular surface thereof with which said pockets or recesses successively communicate, a single valve for controlling the supply of an explosive agent to all of said chambers successively and including a valve having port openings corresponding, respectively, in number and relation to the pockets or recesses in the piston, means arranged in each chamber for exploding the agent within said chamber, and means for opening said chambers and their communicating pockets or recesses to exhaust.
12. In a rotary explosive engine, a piston having pockets or recesses formed therein, a chamber in which said piston is mounted to rotate, and having chambers with which said pockets or recesses successively communicate, means for controlling the supply of explosive agent to all of said chambers successively and including a valve having ports, said valve connected to rotate with said piston, means located in each chamber for exploding the agent within said chambers, and means for opening said chambers, and communicating pockets or recesses, to exhaust.

13. In a rotary explosive engine, a piston having pockets or recesses, a casing in which said piston is mounted to rotate, and having chambers with which said pockets or recesses successively communicate during the rotative movement of the piston, means for controlling the supply of an explosive agent to said chambers, including a valve disk connected to rotate with the piston and having port openings therethrough, and pipe sections respectively communicating with a source of explosive supply and with said chambers, all communication between said pipe sections being controlled by the port openings in said valve disk; means for exploding the charge in said chambers, and means for opening said chambers, and communicating pockets or recesses, to exhaust.

14. In a rotary explosive engine, a piston having radial surfaces to receive the impact of an exploded charge, a casing in which said piston is mounted to rotate, and provided with chambers, into successive communication with which said radial surfaces are brought during the rotative movement of said piston, a valve common to all of said chambers for controlling the supply of an explosive agent to said chambers successively, and means for opening said chambers to exhaust.

15. In a rotary explosive engine, a piston having radiating surfaces, a casing within which said piston is mounted to rotate, and

having chambers into communication with which said radiating surfaces are successively brought during the rotative movement of said piston, means for supplying an explosive agent to said chambers, and including a rotary disk having port openings therethrough, pipe sections respectively communicating with a source of supply of the explosive agent and each of said chambers, the port openings in said disk operating to control the communication between each pair of pipe sections, means for exploding the agent within said chambers, and means for opening said chambers to exhaust.

16. In a rotary explosive engine, a piston having radially arranged surfaces to receive the impact of an exploded charge, a casing in which said piston is mounted to rotate, said casing provided with chambers in the interior annular surface thereof, into successive communication with which said radial surfaces are brought during the rotative movement of said piston, said chambers being inclined to the path of travel of said radial surfaces, a single valve for controlling the supply of an explosive agent to all of said chambers successively, and means for exploding said agent within said chambers, and means for opening said chambers to exhaust.

17. In a rotary explosive engine, a piston having a plurality of pockets or recesses, a casing within which said piston is mounted to rotate, said casing having a plurality of chambers with which said pockets or recesses successively communicate during the rotative movement of said piston, means for controlling the supply of an explosive agent to said chambers, comprising a plurality of pairs of pipe sections, one member of each pair communicating with a source of supply for the explosive agent, and the other member of each pair communicating with a casing chamber, a single revolving valve having port openings arranged to open communication between the members of each pair of pipe sections, means located within each chamber for exploding the agent within said chamber, and means for opening said chambers to exhaust.

18. In a rotary explosive engine, a piston having pockets or recesses, a casing within which said piston rotates, and provided with chambers, into successive communication with which said radiating surfaces are brought during the rotative movement of said piston, pipe sections arranged in pairs corresponding in number to the number of chambers in the casing, one member of each pair of pipe sections communicating with a source of supply for an explosive agent, the other member communicating with a chamber, a rotary valve having a flange, said flange operating between the proximate ends of the members of all the pairs of pipe sec-

tions, and having port openings therethrough to control the communication between said members, means located within each chamber for exploding the explosive charge within said chamber, and means for successively opening said chamber to exhaust.

19. In a rotary explosive engine, a piston having pockets or recesses, a chamber within which said piston is mounted to rotate, and provided with chambers, into successive communication with which said pockets or recesses are brought during the rotative movement of the piston, pipe sections arranged in pairs corresponding in number to the number of chambers in the casing, one member of each pair of pipe sections communicating with a source of supply for an explosive agent, the other member communicating with a chamber in the casing, yielding caps mounted upon the proximate ends of the members of each pair of pipe sections, a rotary valve having a flange arranged to operate between the proximate ends of said caps, and provided with port openings therethrough, means for exploding the explosive charge within said chambers, and means for opening said chambers to exhaust.

20. In a rotary explosive engine, a piston having peripheral pockets or recesses arranged to receive the impact of an exploded charge, a casing within which said piston is mounted to rotate, said casing having explosion chambers formed in the interior annular surface thereof, and also having exhaust passages, into successive and alternate communication with which said pockets or recesses are brought during the rotative movement

of the piston, the communication between said pockets or recesses and the exhaust ports being effected before communication between said pockets or recesses and said chambers is cut off, a common means for controlling the supply of an explosive charge to all of said chambers successively, and means extending into each chamber for exploding said charge within said chamber.

21. In a rotary explosive engine, a casing, a shaft journaled therein, a piston mounted to rotate with said shaft, and within said casing, said casing having chambers and said piston pockets or recesses arranged to be brought successively into communication with each other during the rotative movement of the piston, a valve also mounted to rotate with said shaft, and having port openings for controlling the supply of an explosive agent to all of said chambers successively, commutator rings also mounted to rotate with said shaft, a spark plug extending into each of said chambers, said commutator rings controlling the circuits of said plugs, a disk loosely sleeved upon said shaft and carrying brushes for co-operation with said commutator rings, a lever for rotatably displacing said disk, and means for exhausting the exploded gases from said chambers and pockets or recesses.

In witness whereof, I have hereunto set my hand this 15th day of December 1904, 70 in the presence of the subscribing witnesses.

SHERMAN L. ROBBINS.
